UNITED STATES PATENT OFFICE

PHILIP C. TRAVER, OF LYNBROOK, NEW YORK

PROJECTILE SHOOTING GUN

Application filed August 21, 1931. Serial No. 558,606.

This invention relates to a unique type of toy for shooting projectiles, the structure being such as to justify the adoption of the title gun.

As the latter term implies, my idea is to provide a different and unusual type of gun of a simple and economical and efficient type using air pressure for forcibly dejecting the projectiles flight.

Briefly stated, this improved pneumatic gun is characterized by a drum having a drum like sound producing and developing device and a ball directing barrel, together with means for progressively feeding balls or projectiles into the barrel for successive projection.

In the drawing:

Figure 1 is a plan view of a structure developed in accordance with the present invention.

Figure 2 is a side view of Figure 1.

Figure 3 is a section on the line 3—3 of Figure 1.

The numeral 4 designates the pressure developing or pneumatic impact device. This preferably comprises a pan-like receptacle having a concavo-convex bottom 5 and an upstanding annular rim 6 provided with a channel shaped bear 7 constituting a retaining clamp for the peripheral edge of a flexible drum skin diaphragm 8. Connected with

the rim at a predetermined point is a T-shaped coupling 9 containing an internal shoulder forming nipple 10. Secured to the longitudinal branch of this coupling is a tube 11 which functions as the barrel to deliver the projectile balls. Incidentally I find it ex-

ceedingly practical to use light weight celluloid hollow balls of the type used in games of the ping-pong type. The balls can be inserted one by one by hand for shooting purposes. It is desired however to provide a continuous shooting gun for which reason I find it better to provide a delivery magazine which comprises an upstanding cylinder 13 constituting a container for the superposed balls. On the upper end of this cylinder

there is a removable closing cap 14 having slot 15 cooperable with the retaining pin 16.

In the upper portion of the magazine cylinder

a coiled expansion spring 17 bearing on a follower disk 18 presses down on the balls to deliver them successively into the barrel to occupy the desired shooting position. The numeral 19 in Figure 3 designates ball retaining spring for holding the balls temporarily in place before preparing for projection. The balls are prevented from being sucked into the drum casing by the nipple 10 which functions as a stop or shoulder.

The desired concussion of air is developed by hitting the fist of palm of the hand thoroughly on the flexible skin diaphragm 8. This provides the impact noise amplified by the pan 4. In fact the pan serves somewhat as a resonator producing the desired quality of noise. At the same time this diaphragm action acts against the ball, shooting the ball out through the barrel 11 in an obvious manner. The next succeeding ball in the magazine drops down by gravity and under the action of the plunger or follower 18, and the air in the shooting drum is replenished by the suction intake which is developed as the diaphragm is released by removing hand pressure therefrom.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

What is claimed is:

1. A gun of the class described comprising a pneumatic device embodying a receptacle having a flexible diaphragm defining an air trapping and exhausting chamber, a barrel attached to the marginal rim portion of said container, and means for feeding projectiles into said barrel comprising a container secured to said receptacle in communication with said barrel and a spring-pressed follower in said container.

2. In a device of the class described, an air trapping and noise producing device comprising a pan-like receptacle having a con-

1 cavo-convex bottom and a marginal rim, an outstanding peripheral coupling, a nipple threaded in said coupling, and a closure diaphragm, together with a barrel connected with said coupling and means for feeding projectiles into the barrel.

2 3. In a device of the class described, an air trapping and noise producing device comprising a pan-like receptacle having a concavo-convex bottom and a marginal rim, an outstanding peripheral coupling, a nipple threaded in said coupling, and a closure diaphragm, together with a barrel connected with said coupling and means for feeding projectiles into the barrel, means comprising a magazine with an upstanding cylindrical container and a spring pressed follower in said container.

3 4. A device of the class described comprising a pan-like receptacle having a concavo-convex bottom and upstanding annular rim, said rim having a channel-shaped retainer on its upper edge, a flexible skin diaphragm having an edge portion secured in said retainer, the rim portion of said receptacle being provided on one side with a T-coupling internally threaded, a nipple secured in said internal threads and constituting a stop, an upstanding cylindrical container attached to said coupling and serving as a ball magazine, and a spring pressed plunger in said magazine, together with a ball directing barrel attached to said coupling and extending at right angles to said magazine.

4 5. A gun of the class described comprising a pneumatic device embodying a receptacle having a flexible diaphragm defining an air trapping and exhausting chamber, a tubular coupling secured to said receptacle and projecting outwardly therefrom, a barrel connected to said coupling and means for feeding projectiles into said barrel including a container secured to said coupling in communication with said barrel and a spring pressed follower in said container, said coupling being provided with stop means for preventing movement of the projectiles in the direction of said receptacle.

In testimony whereof I affix my signature.
PHILIP C. TRAVER.
